UNITED STATES PATENT OFFICE.

BRUNO MOMENTHY, OF BALTIMORE, MARYLAND.

IMPROVEMENT IN ROOFING-TILES.

Specification forming part of Letters Patent No. 146,140, dated January 6, 1874; application filed December 1, 1873.

To all whom it may concern:

Be it known that I, BRUNO MOMENTHY, of the city and county of Baltimore and State of Maryland, have invented certain new and useful Improvements in Roofs and Roofing-Tiles, of which the following is a specification:

It is my object in this invention to make a roof as nearly as possible thoroughly fire and water proof, and, I may add, burglar-proof as well. This I accomplish by constructing the roofing-tiles in the manner hereinafter described, whereby when laid to form a roof they may be locked and jointed together on all sides, this being true not only of the tiles in each row, but also of the several rows themselves, the joints being so formed that they will shed the rain or moisture, and prevent it from penetrating the roof. Each tile, moreover, can be locked, by an independent fastening, to the substructure upon which the tiles are laid, so that it will be a matter of difficulty to tear or forcibly remove the tile from its position.

I make my improved tile of clay, iron, or any other material suitable for the purpose.

The accompanying drawing represents the manner in which my invention is or may be carried into effect.

In Sheet 1, Figure 1 is a plan of a tile made in accordance with my invention. Fig. 2 is a section on the line A B, Fig. 1. Fig. 3 is a section of the line C D, Fig. 1. Fig. 4 is a plan of the under side of the tile. In Sheet 2, Fig. 1 is a perspective view of a portion of a roof formed of my improved tiles. Fig. 2 is a section of the same in the line of the pitch of the roof.

Referring to Sheet 1, it will be seen that the tile is formed with a groove, *a*, on one of its side edges, and with an overhanging flange or tenon, *b*, on the other side edge, the groove being on the outer face, and the tenon on the inner face, of the tile. Exterior to the flange or tenon *b* is the slanting lip *c*; and the top of the inner one, *d*, of the two flanges that form the wall of groove *a* is also made slanting or beveled, as shown at *d'*. Each tile is formed in this way on its side edges, the object being to provide means for the interlocking of the several tiles in each row; and, it will be seen,

supposing another tile be laid alongside and to the left of the tile in Fig. 2, Sheet 1, that the tenon *b* on this second tile will fit in the groove *a* of the first tile, while the beveled or slanting lip *c* of the second tile will lap upon, and over, and cover, the beveled top *d'* of the flange *d* of the first tile. This is indicated in Fig. 1, Sheet 2, in the middle row of the tiles, A. In the manner thus indicated, the tiles can be laid in rows, and the tiles forming the row will be interlocked and held firmly together. By means of the slanting overhanging lip *c*, in conjunction with the correspondingly-beveled flange *d*, the water is deflected, and prevented from entering the joint. The slanting overhanging lip *c* does not extend appreciably below the beveled top of flange or wall *d*, and is removed from the main face of the tile, and the joint is thus quite above, and out of contact with, any water that may gather or remain on the tile.

Referring again to Sheet 1 of the drawing, each tile is formed at its top edge with a groove, *e*, and at its bottom edge with a flange or tenon, *f*, exterior to which is an overhanging slanting lip, *g*. The inner flange or wall of groove *e* is slanting or beveled on top, as shown. (See Fig. 3.) These parts are substantially similar in construction and operation to the parts previously described for locking together the contiguous sides of the tiles in each row; but in the new position they are designed to lock together, one with another, the several rows of tiles. This is seen in Figs. 1 and 2, Sheet 2, and particularly in Fig. 2, where the interlocking of the grooved tops of the tiles of one row with the tenoned bottoms of the tiles of the row next above is clearly represented.

It will be seen, also, that there is the same provision here as at the sides of the tiles for shedding the water and preventing it from entering the joints. I prefer to provide, on the under side, and near the top of each tile, one or more lugs or studs, *h*, which catch over the stringers or strips *i* on which the tiles rest, and thus serve, to some extent, to assure the position of the tiles.

The tiles can be made very thin and light, and are, preferably, provided with ribs *j k* for strengthening them.

The tenons and grooves by which the tiles

are interlocked have a taper or wedge-tile form, so that the parts are tightly drawn together, and a close connection is made. But it is designed, also, to fill the joint with thin mortar or cement, in order to make it absolutely water-proof, even when the roof has a very low pitch. I provide the tile, on its back or under side, with an eye, *l*, intended to receive the fastening device, by which the tile may be bound to the roof. Such a device is shown in Fig. 2, Sheet 2, consisting of a metallic hook, *m*, which passes up through the substructure or roof-frame, enters the eye *l*, and is held to the roof-frame by a pin passing transversely through that part of its shank which extends below said frame. In lieu of this device other means of fastening can be employed—as, for instance, a piece of wire passed through the eye *l*, with its ends carried down through the hole or slit in the roof-frame, and then twisted or knotted. In this way the tiles will be secured to the roof so firmly that they cannot be blown off by the wind, and they will, as well, make it very difficult, if not impossible, for burglars to remove them in order to break into or through the roof.

It will be noted that the grooves are formed on the exterior face of the tile, while the tenons are on the under face or side of the same.

In laying the tiles on a roof it is desirable that they should be placed so that those in one row will break joint with those in the row or rows adjoining.

I have thus described the manner in which I prefer to construct the tile as a whole. It will,

however, be understood that its construction may be varied without departure from the principle of my invention. These variations may be not only in the respects heretofore intimated, but also as regards the devices which form the peculiar beveled lap-joint between any two tiles. These devices are represented as formed on both the top and bottom and the side edges of the tiles, and it is in this form that I prefer to use them. But cases may arise in which the beveled lap-joint will be required only between different rows of tiles, and not between tiles of the same row. In this case the devices to form the beveled lap-joint would be formed only on the top and bottom edges of the tile, and not on its sides. In like manner the joint could be dispensed with at the ends—that is to say, the top and bottom edges—of the tiles, and applied only to the sides of the same.

What I claim, therefore, is—

As a new manufacture, roofing-tiles, provided at their ends or sides, or both ends and sides, with grooves, tenons, and lapping pieces, constructed as shown and described, to form the herein-specified beveled lap-joint between the contiguous edges of any two tiles.

In testimony whereof I have signed my name to this specification before two subscribing witnesses.

B. MOMENTHY.
